ROSARY BRACELET

Warwick Joseph White and Kevin Francis Davern,
Melbourne, Victoria, Australia

Application January 27, 1954, Serial No. 28,690

Claims priority, application Australia December 4, 1953

Term of patent 14 years

(Cl. D45—4)

To all whom it may concern:

Be it known that we, Warwick Joseph White and Kevin Francis Davern, both citizens of the Commonwealth of Australia, residing at Melbourne, in the State of Victoria, Commonwealth of Australia, have invented a new, original, and ornamental Design for a Rosary Bracelet, of which the following is a specification, reference being had to the accompanying drawing, forming part thereof.

Fig. 1 is a front perspective view of the rosary bracelet, showing our new design.

Fig. 2 is a top plan view thereof shown in open condition.

We claim:

The ornamental design for a rosary bracelet, substantially as shown.
